UNITED STATES PATENT OFFICE.

WILLIAM H. BROOKS, OF WEST POINT, NEW YORK.

STEAM-RADIATOR.

SPECIFICATION forming part of Letters Patent No. 291,026, dated January 1, 1884.

Application filed May 7, 1883. (No model.)

To all whom it may concern:

Be it known that I, WILLIAM H. BROOKS, of West Point, county of Orange, and State of New York, have invented certain new and useful Improvements in Steam-Radiators, of which the following is a full, clear, and exact description, reference being had to the accompanying drawings, and to the letters of reference marked thereon.

10 My invention has relation to that class of radiators which are commonly exposed in a room for heating purposes, ordinarily known as "steam-radiators" or "steam-heaters," and adapted for the reception of steam at high or 15 low pressure or any other heat-conducting fluids or liquids. The several improvements hereinafter specified may, however, be employed advantageously in radiators of the class known as "indirect" radiators, or those which 20 are located in an air-conducting flue at a distance from the space to be heated.

The objects of my invention are, primarily, to produce a simple, cheap, and durable radiator wherein the heat-conducting fluid shall 25 be suitably subdivided within the structure, causing a positive circulation through the several tubes thereof, and exposing a large heating-surface of metal to the space to be warmed, and to so arrange and construct the 30 base and the tubes that both may be made of cast metal, be readily united for use or dis-united for repairs, and the structure be automatically drained of condensed steam without interfering with the heat-producing qualities 35 of the apparatus. To accomplish all of this, my improvements involve certain novel and useful peculiarities of construction, relative arrangements, or combinations of parts and details of manufacture, all of which will be hereinafter fully described, and then pointed out in 40 the claims.

In the accompanying drawings, forming part of this specification, Figure 1 is a sectional elevation, showing the construction and arrangement of the base of the radiator, and one of the circulating-tubes or clusters of small pipes in place therein, the section through the cluster of pipes being represented as upon a vertical plane passing through line a x of 45 Fig. 2. Fig. 2 is a plan of the bottom of one of the clusters shown in Fig. 1. Figs. 3 and 50 4 are horizontal sections upon planes passing

through lines y y and z z , respectively, of Fig. 5. Fig. 5 is an elevation of the cluster shown in Fig. 1, the same being detached 55 from the base. Fig. 6 is an elevation of a cluster, detached from any base, the same being made in all respects like that of Fig. 1, except that instead of four small tubes only two are required to form the cluster; and Fig. 60 7 is a plan of the bottom of the cluster shown in Fig. 6.

In all the figures like letters of reference, wherever they occur; indicate corresponding parts.

65 A is the base-piece of the radiator. This is made of cast-iron, intended to rest upon the floor, and to support the radiating-tubes above it, being for that purpose provided with a series of screw-threaded openings calculated to receive the correspondingly-threaded ends of the tubes.

The drawings represent the base as made to receive only two lines of the radiating-tubes, but, obviously, the width of the base may be 75 increased, and as many lines or rows of tubes be employed as may be required, the base being properly fashioned to receive them. The length of the base is not limited, nor its outline, which may be square, rectangular, or 80 circular.

Within the base, and preferably cast therewith, are the dividing-strips d d , extending under all the threaded openings, and below each strip is a pocket, e , into which the water or condensed steam settles and closes the communication between the spaces on opposite sides of the strips, which otherwise would be free and open. The radiating-tubes are also made of cast-iron, each main tube being composed of a number of smaller tubes, the openings through which are united at top and bottom, affording ample room for the passage of steam and affording an extended area of exterior surface (between the top and bottom) 95 which is exposed to the air, the latter being free to circulate between the several small tubes. These small tubes in each cluster are arranged in pairs, as a b , a b . If there be more than four, then they also are arranged in 100 pairs.

In the base of the cluster is the dividing-strip e , calculated to rest upon the strip d as soon as the pipe is turned into its seat to a

proper degree, this base being provided with a thread or winding suitable for the purpose. Each of the small tubes in the cluster has a free open way through its base, as plainly indicated in the Figs. 1 and 2, the openings from tubes *a* being on one side of the strip *c*, and those of tubes *b* being on the opposite side. At their upper ends these tubes all unite in a common chamber, as indicated in Figs. 1 and 3. The clusters so formed and arranged is cast in a single piece, using the sand core as usual. There then remains only the base part of the cluster to be fitted to enter the seat provided for it; and, this being circular work, may be 15 quickly and cheaply accomplished.

The division-strips *d* being located, as explained, under each row of tubes, there is an inlet side and an outlet side for each one employed in the make-up of the apparatus. With 20 two rows, we have the inlet-port, as at *g*, and the outlet or exit, as at *h*, in the base *A*. Steam entering at *g* takes the course shown by the arrows, ascends tubes *a* in each cluster and descends through *b*, and passes to the outlet *h* 25 through the several rows. Thus we have a perfect circulation through the radiator. The pressure of the steam on the water in trap *e* is equal on both sides of the dividing-strip *d*, so that the water in the trap will not be disturbed, 30 but by its presence will compel the circulation in the manner indicated. When too much water collects in the base *A*, it is automatically drained through the outlet *h*.

The outlet and inlet ports are represented 35 as being located on the ends of the radiator. They might be arranged at any points of the sides, if desired—one on one side and one on the other—or both on one end, it being only necessary that they fall on opposite sides of 40 the divisions into which the base is separated. This makes it very convenient to locate the radiator and to carry the conduit to and from it in any desired direction.

The clusters of tubes at top and bottom are 45 blended into one, so that they are in effect, when being handled, the same as a single tube; but they possess a much greater surface for contact with the air of the room, and, moreover, they compel (with the adjuncts named) 50 a complete circulation through them of the heating-fluid, and do not depend upon mere expansion, as in the single-tube expansion-radiators heretofore mainly constructed.

In the circulation-radiators of former constructions, the base of the device has been divided into an inlet and outlet chamber; but the tubes, being separate, are with difficulty assembled and with great difficulty dismounted, especially when an interior tube has been required to be removed. In the latter case it 60

is necessary to first remove the exterior rows of tubes in order to gain access to those of the interior rows.

With my improved form of circulating-tube, any one tube in the radiator may be 65 quickly detached by unturning it without disturbing any of the adjacent tubes; and, if desired, its threaded seat may be plugged up and the remainder of the radiator operated the same as if all the tubes were in place.

When constructed and arranged for operation substantially in accordance with the foregoing explanations, the improved device will be found to admirably answer the purposes or objects of the invention as previously set forth.

It is not essential that the small tubes *a* and *b* be made circular in cross-section, as indicated. They may be of any form which is convenient to cast, and they may be assembled in the clusters in any way to produce any required outline.

Having now fully described my invention, what I claim as new, and desire to secure by Letters Patent, is—

1. In combination with the radiator-base, 85 one or more division-plates running the entire length of said base and located beneath the centers of the tube-holes, and the traps or depressions in the base beneath the division-plates arranged to close the openings between 90 the several compartments at the lower margins of said division-plates, substantially as shown and described, and for the purposes set forth.

2. In a radiator-base, the division-plates 95 running the entire length thereof, located beneath the centers of the tube-holes, and the traps or depressions below said division-plates arranged to close the communication between the several compartments of the base, except through the medium of the superposed circulating-tubes, all combined and arranged substantially as and for the purposes set forth.

3. In a steam-radiator of the character herein set forth, the combination, with the base 105 having the division-plates extending beneath the centers of the tube-holes, of the herein-described clusters of radiator-tubes arranged in pairs cast in a single piece with their cross-strips, and the traps or depressions beneath 110 the plates in the base, all arranged to compel a circulation through the tubes, substantially as shown and described.

In testimony that I claim the foregoing I have hereunto set my hand in the presence of two 115 witnesses.

WILLIAM H. BROOKS.
